(57) CLAIM

The ornamental design for a signal transmission pin, as shown and described.

DESCRIPTION

FIG. 1 is a first perspective view of a signal transmission pin showing our new design from a front end.

FIG. 2 is a second perspective view of the signal transmission pin of FIG. 1, shown from a rear end that is opposite the front end.

FIG. 3 is a front plan view of the signal transmission pin of FIG. 1.

FIG. 4 is a rear plan view thereof.

FIG. 5 is a top plan view thereof.

FIG. 6 is a bottom plan view thereof.

FIG. 7 is a right side elevation view thereof.

FIG. 8 is a left side elevation view thereof.

FIG. 10 is a fourth perspective view of the signal transmission pin of FIG. 1, shown from the rear end. Here, contact pins are again shown having been inserted into the opposing female ends of the signal transmission pin.

FIG. 11 is a first perspective view of a bulkhead and signal transmission pin, showing our new design in a first embodiment and taken from a front end.

FIG. 12 is a second perspective view of the bulkhead and signal transmission pin of FIG. 11, shown from a rear end.

FIG. 13 is a front plan view of the bulkhead and signal transmission pin of FIG. 11.

FIG. 14 is a rear plan view thereof.

FIG. 15 is a top plan view thereof.

FIG. 16 is a bottom plan view thereof.

FIG. 17 is a right side elevation view thereof.

FIG. 18 is a left side elevation view thereof.

FIG. 19 is a third perspective view of the bulkhead of FIG. 11. Here, a signal transmission pin is shown residing within a bore of the signal bulkhead; and,

FIG. 20 is a fourth perspective view of the bulkhead of FIG. 11. Here, o-rings have been added. The broken lines in the drawings depict portions of the signal transmission pin that form no part of the claimed designs.
